COMBINED TUBULAR CONTAINER AND
APPLICATOR

Raymond C. Rupp, Kendallville, Ind.

Application April 23, 1940, Serial No. 331,246

7 Claims. (Cl. 15—135)

The invention aims to provide a new and improved article in which a tube is employed to contain a paste or liquid and to extrude same as required to an applicator carried by said tube, the tube acting as a handle for operating the applicator and enabling effective use thereof to apply the extruded paste or liquid to any desired surface.

In carrying out the above end, a further object is to provide the device with two applicator surfaces which converge outwardly from one end of the tube and join each other along a ridge line, giving greater applicator area, enabling more convenient use of the device, and providing a rather sharp corner or ridge which may be used to apply the extruded paste or liquid in angular places, for example, those existing between the welts and uppers of shoes.

A still further object is to provide a device of the class described which is normally sealed in a novel way yet will permit extrusion simply by pressing inwardly upon the walls of the tube.

With the foregoing and minor objects in view, the invention resides in the novel subject matter hereinafter described and claimed, description being accomplished by reference to the accompanying drawings.

Fig. 1 is a vertical sectional view partly in elevation showing one form of the invention with the discharge openings in the tubular container sealed.

Fig. 2 is a view similar to Fig. 1 but showing the manner in which the tube contents can be extruded.

Fig. 3 is an end elevation looking down on Fig. 1.

Fig. 4 is a view similar to Fig. 3 with the applicator pad removed.

Fig. 5 is a side elevation partly in section showing a different form of construction.

Fig. 6 is an end elevation looking down on Fig. 5.

Fig. 7 is a fragmentary elevation partly in section showing a still further form of construction, the discharge opening being sealed.

Fig. 8 is a view similar to Fig. 7 but illustrating the manner in which the tube contents may be extruded.

Fig. 9 is an end elevation looking down on Fig. 7.

Fig. 10 is a detail sectional view through the elastic disk of Figs. 7, 8 and 9 showing the manner in which it is cut to provide the discharge opening and sealing tongue of said figures.

In Figs. 1 to 4, 10 denotes a tube of such nature that opposite sides thereof may be readily pressed toward each other to extrude the tube contents 11. This tube is provided with an end wall consisting of two halves 12 and 12' which converge outwardly and join each other along a ridge line 13, each half being formed with an opening 14

spaced from said ridge line. An applicator pad is cemented or otherwise suitably secured against the outer side of the end wall 12, 12', said applicator pad being preferably formed from sponge rubber and consisting of two outwardly converging halves 15 and 15' joined along a ridge line 16 which rests on the ridge line 13 of the tube end wall. This ridge portion of the applicator is formed with a small opening 17. The restricted portion of the applicator within the dotted line 18 (Fig. 3) is free from connection with the tube end wall, said portion extending over the ridge 13 of said end wall and preferably to the lower edges of the openings 14. Within this restricted portion of the applicator, the opening 17 is located.

The above mentioned restricted portion of the applicator pad is denoted at 19 and it will be observed that it normally lies tightly against the end wall 12, 12' of the tube 10 to form a seal between the openings 14 and the opening 17. However, when the sides of the tube are pressed inwardly to extrude some of the contents 11, said contents must outwardly bulge (Fig. 2) the portion 19 in order to pass through the openings 14, on to the opening 17, and through the latter. When pressure on the side walls of the tube is discontinued, extrusion stops and when the applicator halves 15 and 15' are used to apply the extruded substance, the pressure necessarily again forces the outwardly bulged applicator portions into tight sealing contact with the tube end wall.

By providing the applicator with two converging halves and a corner or ridge connecting them, the effective surface of the applicator is increased, the entire device may be held in a more convenient position while using same, and a rather sharp corner is provided to reach into angular places where the extruded substance is to be applied, for example, in the angles between the welts and uppers of shoes.

In Figs. 5 and 6, the tube 10^a is provided with an end wall 12^a of the same construction as the end wall above described, the two halves of said end wall being formed with openings 14^a corresponding to the openings 14 while the ridge of said end wall is provided with an opening 20. The applicator pad 15^a may be identical with the pad above described, but it is secured throughout its inner area to the end wall 12^a and is provided with self-closing slits 17^a in the portions thereof which extend across the openings 14^a and 20. The device has the same advantages as those above set forth. It will be obvious that the slits 17^a are normally closed and thus, form seals, yet that when the sides of the tube are inwardly pressed, the tube contents will be extruded through said slits, due to the stretch of the sponge rubber or the like permitting said slits to open somewhat.

In Figs. 7 to 9, the tube 10^b is provided with an end wall 12^b shaped as above described, but preferably of considerably less pitch, the ridge of said end wall 12^b being formed with a comparatively large opening 14^b. A disk 21 of rubber or the like is cemented against the lower sides of the converging halves of the end wall 12^b and is provided in its ridge portion with an opening 22 under the opening 14^b. A tongue 23 is provided to normally close the opening 22, one end of said tongue being integrally joined to the disk 21 at one end of the opening 22. The tongue 23 extends obliquely through this opening 22 to the exterior of the disk 21 and has its free end positioned within the opening 14^b, said free end resting upon the corner 24 between the upper side of the disk 21 and the end wall of the opening 22 subjacent to said free end of said tongue. The opening 22 and tongue 23 may be simultaneously formed by cutting a U-shaped slit in the disk 21 as shown in Fig. 9, the free end of the tongue and the contiguous end of the opening being inclined so that the corner 24 will be provided to underlie and contact with said free end of the tongue to normally seal the tube.

When the sides of the tube 10^b are pressed toward each other, the tube contents will be extruded, causing the tongue 23 to outwardly yield until the pressure is stopped, whereupon the resiliency of said tongue again closes it. The extruded material may be applied to any desired surface by using either half of the end wall 12^b as an applicator.

From the foregoing taken in connection with the accompanying drawings, it will be seen that novel and advantageous provision has been made for carrying out the objects of the invention. While preferred details have been disclosed, minor variations may of course be made within the scope of the invention as claimed.

I claim:

1. A combined container and applicator comprising a tube having a substantially rigid one-piece end wall, said end wall consisting of two substantially rigid halves converging outwardly and joined integrally to each other along a ridge, and a resilient one-piece pad having substantially flat converging halves also joined integrally to each other along a ridge, said pad halves being secured upon one side of said end wall halves and said ridges being in contact with each other, and an outlet passage from the interior to the exterior of said tube including an opening through the outermost of said ridges, said pad having an integral yieldable portion which normally obstructs discharge of the tube contents through said passage.

2. A combined container and applicator comprising a tube having a substantially rigid one-piece end wall, said end wall consisting of two substantially rigid halves converging outwardly and joined integrally to each other along a ridge, a resilient one-piece applicator pad having substantially flat converging halves also joined integrally to each other along a ridge, said pad halves being secured upon the outer sides of said end wall halves and the two aforesaid ridges being in contact with each other, and a discharge passage from the interior to the exterior of said tube including an opening through the ridge of said pad, said pad having an integral

yieldable portion which normally obstructs discharge of the tube contents through said passage.

3. A combined container and applicator comprising a tube having a relatively rigid end wall formed with an opening, and a resilient applicator pad secured against the outer side of said end wall and extending over said opening, said pad having an opening offset from said opening of said end wall, said pad being free of attachment to said end wall from one of said openings to the other, whereby the tube contents, when being extruded, must outwardly bulge a restricted portion of the pad in passing from the wall opening to the pad opening, said restricted portion of the pad normally constituting a seal between the two openings.

4. A combined container and applicator comprising a tube having an end wall, said end wall consisting of two halves converging outwardly and joined to each other along a ridge line, and a resilient applicator pad having substantially flat converging halves joined to each other and secured upon the outer sides of said converging halves of said end wall, each of said converging halves of said end wall having an opening spaced from said ridge line, said pad having an opening directly over said ridge line, a restricted portion of said pad extending over said ridge line from one of said end wall openings to the other thereof and being free of attachment to said end wall, said pad opening being in said restricted portion, whereby the tube contents, when being extruded, must outwardly bulge said restricted portion of said pad in passing from the end wall openings to the pad opening, said restricted portion normally constituting a seal between said end wall openings and said pad opening.

5. A combined container and applicator comprising a tube having an end wall, said end wall consisting of two halves converging outwardly and joined to each other along a ridge line, and a resilient applicator pad having substantially flat converging halves joined to each other and secured upon the outer sides of said converging halves of said end wall, said end wall having openings in said converging halves thereof and in its ridge, the portions of said pad extending over said openings being formed with self-closing slits, said openings and slits serving as discharge means for the tube contents.

6. A combined container and applicator comprising a tube having an end wall formed with an opening, an elastic disk secured against said end wall and having an opening aligned with said end wall opening, and a tongue extending obliquely through said disk opening and having one of its ends integrally joined to said disk at one end of said disk opening, the free end of said tongue extending to the exterior of said disk and resting upon the corner at which the outer side of said disk joins the subjacent end wall of said disk opening.

7. A structure as specified in claim 6; said end wall having two outwardly converging halves which join each other along a ridge line, said opening of said end wall being in the ridge thereof, said elastic disk being secured against the inner sides of said end wall halves, said free end of said tongue projecting through said end wall opening.

RAYMOND C. RUPP.
